UNITED STATES PATENT OFFICE.

JOHN J. MCNEELY, OF JACKSON, MISSOURI, ASSIGNOR, BY DIRECT AND MESNE ASSIGNMENTS, TO UNIVERSAL AUTOMATIC BOTTLE DISPENSING MACHINE COMPANY, OF QUINCY, ILLINOIS, A CORPORATION OF ILLINOIS.

AUTOMATIC DISPENSING MACHINE.

Application filed March 19, 1924. Serial No. 700,356.

This invention relates to new and useful improvements in automatic dispensing machines.

An important object of the invention is to provide a machine of the coin controlled type which will automatically dispense the commodity placed therein when operated by a person.

A further object of the invention is to provide a cabinet for housing the dispensing mechanism and the commodity to be dispensed thereby.

A still further object of the invention is to provide a cabinet of the above mentioned type which is suitable for icing the commodity when the machine is used for dispensing bottled beverages.

Another object of the invention is to provide a novel form of conveyor for carrying the commodity from the feeding point to the point of discharge.

Still another object of the invention is to provide suitable mechanism for preventing but one article to be dispensed at a time and for insuring the proper resetting of the mechanism after an article has been dispensed.

A further object of the invention is to provide extension compartments to the main body portion of the cabinet for carrying a surplus supply of articles and for displaying a desired number of the articles for illustrating the type of commodity being handled by the machine.

Other objects and advantages of the invention will be apparent during the course of the following description.

In the accompanying drawings forming a part of the specification and in which like numerals are employed to designate like parts throughout the same:

Figure 1 is a vertical sectional view of the automatic dispensing machine embodying this invention,

Figure 2 is a fragmentary transverse sectional view taken upon lines II-II of Fig. 1,

Figure 3 is a transverse sectional view taken upon line III-III of Fig. 1,

Figure 4 is a detail vertical sectional view showing an enlargement of the coin controlling mechanism which is operated by a purchaser and illustrates the structure which will prevent the dispensing of an ar-

ticl if a coin has not been deposited in the machine, and

Figure 5 shows a similar view to Fig. 4, but illustrates the operation of the manually actuated mechanism after a coin has been deposited for permitting the said mechanism to be operated for causing an article to be dispensed.

In the drawings, wherein for the purpose of illustration is shown a preferred embodiment of this invention, the numeral 5 designates the rear wall of the cabinet which is

employed for housing the dispensing mechanism and the commodity being dispensed by such mechanism. The numeral 6 designates the bottom wall of this cabinet while

the numerals 7 and 8 designate the top and front walls respectively. The sides of this cabinet are closed by the side walls 9 which are best illustrated in Figs. 2 and 3. In

Figs. 1 and 2, the top wall 7 is illustrated as being provided with a hinged door 10 having a handle 11 carried thereby which will permit the operating of said door.

Formed integrally with the bottom wall 6 is an extension 6^a which forms the bottom wall of a storage compartment designated in general by the numeral 12. This storage compartment 12 is provided with side walls 13 and a front wall 14, as illustrated.

In Fig. 1, the front wall 14 of this storage compartment is illustrated as being provided with a door 15 at its upper portion and a second door 16 at its lower portion.

It is to be understood that suitable locking mechanism is provided for each of these doors 15 and 16 for preventing an unauthorized person from gaining access to the interior of the storage compartment 12. The top wall 7 is also provided with an extension 7^a while the side walls 9 are illustrated in Fig. 3 as being provided with extensions 9^a.

These extensions 7^a and 9^a are employed for forming a display compartment which is further formed with shelves 17 upon which the bottles B or other commodity are to be positioned. In Fig. 3, the front longitudinal edges of the side wall extensions 9^a are illustrated as being provided with guide

grooves 18 within which a glass carrying frame 19 is slidably positioned. It will be understood that the glass 20 carried by this frame 19 will permit a purchaser to view the bottles B positioned upon the shelves

17 and will thereby be able to familiarize himself with the type of commodity being dispensed by the machine.

The storage compartment 12 is illustrated in Fig. 1 as being provided with staggered, downwardly sloping, transversely extending shelves 21 which are so arranged that bottles B placed in the compartment through the door 15 will travel, due to the force of gravity, through a tortuous path over the various shelves towards the direction of the bottom platform 22 which is provided with an upwardly curved outer edge 23 which is intended to stop the travel of the bottles when they arrive at the same. It will be understood that these bottles may be withdrawn from the storage compartment 12 through the opening which is closed by the door 16. Placed within the bottom of this storage compartment 12 is a drip pan 24 which is employed for catching all foreign matter accidentally placed within the compartment 12 and also for catching moisture or water of condensation which will drop from the bottles B due to the icing of the same which will be described at a later point.

The front wall 8 of the cabinet is provided with an elongated opening 25 through which access may be gained to the interior of the cabinet by withdrawing the glass carrying frame 19 from the guide grooves 18. Connected to this front wall 8 in axial alignment with the opening 25 is an L-shaped, entirely closed chute 26 which extends downwardly to the point 27 where it is formed with an opening through which the bottles B, placed in the chute through the opening 25, will be discharged. One wall of this chute 26 is continued in the form of a partition or guide strip 28 which extends downwardly and engages at its lower end the bottom wall 6 of the cabinet.

Suitably journaled in the bearings 29 are the upper and lower, transversely extending shafts 30 and 31 respectively. Suitably mounted upon the lower shaft 31 is a double sprocket wheel 32 while similarly mounted upon the upper shaft 30 is a second, double sprocket wheel 33. Mounted upon these sprocket wheels 32 and 33, for rotation therewith, is a pair of link chains 34 which carry the suitably spaced, transversely extending bars 35 which are equi-spaced in respect to each other. Secured to the front wall 8 of the cabinet and the inner face of the partition or guide strip 28 is an arched guide 36 which is positioned a proper distance from the periphery of the double sprocket wheel 32 for permitting the transversely extending bars 35 to slightly engage the same.

It is to be understood that these bars 35 are secured to the double sprocket chain 34 in spaced relation to each other for receiv-

ing the bottles that are discharged at the point 27 from the chute 26. It will also be seen that there is but sufficient room between the bars 35 to receive one bottle only. It will also be seen that the bottles that are placed in the chute 26 will feed, due to the force of gravity, into the pockets formed by the bars 35 and will be conveyed from the point 27, downwardly in engagement with the partition 26, around the periphery of the lower, double sprocket wheel 32 in engagement with the arched guide 36 and upwardly on the opposite side of the conveyor until they reach the opening 37, formed in the front wall 8 of the cabinet, through which they are discharged onto the tray 38 which projects outwardly from the front wall 8. It will also be seen, by inspecting Fig. 1, that this tray 38 forms a top wall for the storage compartment 12.

For the purpose of preventing the bottles B from being dropped from their respective pockets through the space between the separate chain forming the pair of link chains 34, a guide strip 39 is positioned for extending longitudinally between the said chains in parallelism with the partition 28. A second guide strip 40 extends in parallelism with the lower portion of the front wall 8 between the lower, double sprocket wheel 32 and the discharge opening 37. At the upper end of this second guide strip 40, there is formed a substantially U-shaped bracket 41 within which is housed a trigger 42 which is spring pressed outwardly into the path of travel of the bars 35 by the spring 43. It is to be understood that this trigger is provided with a beveled outer end 44 which is adapted to be engaged by the bars 35 during their upward travel for being forced out of the path of travel of said bars against the tension of the spring 43. It is, also, to be understood that after one of the bars 35 has passed the trigger 42 and has carried a bottle in alignment with the discharge opening 37, that the trigger 42 will again be forced outwardly, by the spring 43, for substantially shooting the said bottle through the opening 37 onto the tray 38.

For the purpose of insuring the stopping of the bottle conveying means in the exact position illustrated in Fig. 1, after a bottle has been dispensed onto the tray 38, the upper shaft 32 is provided with a star wheel 45 which is engaged, as best illustrated in Figs. 1 and 2, by the roller 46 which is carried by the yoke 47. This yoke is suitably secured to a bar 48 which extends upwardly through a suitable aperture formed in the bracket 49 that projects laterally from one of the side walls 9 of the cabinet. There is also provided a bracket 50 which is secured to the front wall 8 of the cabinet and pivotally carries a link 51 which has an

elongated slot 52 at its outer end that slidably engages a pin 53 carried by the bar 48. Encircling this bar 48 and engaging the link 51 at its lower end and the bracket 49 at its upper end is a tension spring 54 which is employed for forcing the roller 46 downwardly upon the tread of the star wheel 45. It will be seen by this mechanism that the conveyor carrying the bottles B will always stop when the roller 49 rests in one of the cavities between adjacent points of the star wheel 45.

The mechanism employed for actuating the bottle conveying mechanism includes a ratchet wheel 55 which is keyed to the shaft 30, as best illustrated in Figs. 1 to 3 inclusive. There is also pivotally secured to the upper shaft 30 a lever 56 which carries the pawl 57 that is adapted for engaging the teeth of the ratchet wheel 55. The lever 56 is provided with a spring element 58 that engages the pawl 57 for retaining its outer end against the ratchet wheel 55.

Suitably mounted upon the outer surface of the front wall 8 is a box 59 which carries the coin controlled mechanism. The lower wall of this box, as illustrated in detail in Figs. 1, 4 and 5, is provided with a raised platform 60 upon which is slidably positioned a plunger 61. This plunger is retained in engagement with the upper face of the platform 60 by means of the guide 62. The outer end of this plunger 61 is provided with a laterally projecting pin 63 which is slidably received with an elongated opening 64 formed in the operating lever 65. This lever 65 projects upwardly through the top wall of the box 59 and terminates in a handle 66. Connected to this operating lever 65 is a rod 67 which extends through a suitable opening formed in the front wall 8 of the cabinet and is connected at its inner end to the lower end of the lever 56 which carries the pawl 57. It will be seen from this construction that when the operating lever 65 is pivoted, as indicated in dotted lines in Figs. 4 and 5, the plunger 61 will be reciprocated along the surface of the platform 60. Positioned above the platform 60 and inwardly of the guide 62 is a stop 68 which is pivoted at 69 and is provided with an elongated slot 70 which receives a pin 71 carried by the side wall of the box 59. It will be seen by inspecting Figs. 1, 4 and 5 that the lower edge of the stop 68 is provided with a curved surface 72 and a flat outer end 73. In Fig. 4 the operating lever 65 and plunger 61 are shown in dotted lines in partially actuated positions. It will be noted, however, that the plunger 61 is prevented from moving the proper distance inwardly for causing the rod 67 to sufficiently operate the dispensing mechanism for discharging a bottle B upon the tray 38.

A coin chute 74 is illustrated in Figs. 1, 65 4 and 5 and is employed for conveying the coin C into the box 59 and discharge the same into a position in front of the inner end of the plunger 61 while the latter is in the full line position illustrated in Fig. 4. 76 After this coin has been dropped in front of the plunger 61, the operating lever 65 may be actuated for forcing the said coin into engagement with the curved surface 72 of the stop 68 for moving the same upwardly 75 into the dotted line position illustrated in Fig. 5. With the stop in its dotted line position, the plunger 61 will be free to move inwardly to its dotted line position as illustrated in Fig. 5. This permitting of the 80 plunger 61 to move as illustrated in Fig. 5 will allow the rod 67 to be moved sufficiently for rotating the shaft 30, due to the provision of the ratchet wheel 55, pawl 57, and lever 56, to cause the conveyor chain to 85 carry one of the bottles B into alinement with the discharge opening 37 where the trigger 42 will force the said bottle out upon the tray 38.

In Figs. 1, 4 and 5, the rod 67 is illustrated as being encircled by a spring 75 which engages, at its inner end, the front wall 8 of the cabinet and at its outer end the stop washer 76 which is suitably keyed to the lever 67. It will be seen that this spring 95 76 will cause the rod 67 to return to its inoperative position after having been actuated for moving the conveyor to dispense a bottle.

There is also illustrated in these three figures an opening 77 through which the coins C will drop into the coin box 78.

In Fig. 1 there is illustrated a cake of ice 79 which is intended to be positioned within the cabinet through the hinged door 10 carried by the top wall 7 of the cabinet. The said cabinet is intended to be provided with the water W which is intended to be maintained at the level of the overflow pipe 80. There is also provided a drain opening 81 110 through which the water may be discharged from the cabinet. It will be seen by placing this ice water W in the cabinet that the bottles B will be retained within this water for a sufficient period, before being dispensed, for thoroughly chilling the contents of the same. The bottles, before being submerged in the ice water W, will also be cooled on account of the fact that they are in the cabinet which will naturally be retained at a low temperature. It is also intended that the bottles in the storage compartment 12 will be slightly cooled by the presence of the ice water on the other side 115 of the front wall 8 of the cabinet.

It is believed that the construction, manner of assembling the various elements embodying this machine, and the operation

of the same will be understood from the above detailed description. Therefore, no further explanation is deemed necessary.

It is to be understood that the form of this invention herewith shown and described is to be taken as the preferred example of the same, and that various changes in the shape, size, and arrangement of parts may be resorted to without departing from the spirit 10 of the invention or the scope of the subjoined claims.

Having thus described the invention, I claim:—

1. In an apparatus of the class described, 15 a cabinet having a discharge opening, an article carrier in the cabinet adapted to feed bottles to a position in alinement with said opening, said carrier including transversely extending bottle supporting bars, means 20 rendered active by the movement of said bars for forcing the bottles from the carrier through the discharge opening, said means including a bracket in alinement with said discharge opening, a trigger carried by said

25 bracket, resilient means for normally holding said trigger partially in the path of travel of said bars, and a beveled surface on said trigger adapted to be engaged by said bars during travel for moving the trigger against the action of said spring, whereby 30 when the trigger is released from a bar it will fly forwardly to strike and to discharge an article.

2. In an apparatus of the class described, 35 a cabinet having a discharge opening, means for retaining ice water at a predetermined level in said cabinet, a bottle carrier in the cabinet having a path of travel through said water and adapted to feed bottles in alignment with said opening, said carrier carrying transversely-extending bottle-supporting bars, and means rendered active by the movement of said bars for forcing the bottles 40 from the carrier through the discharge opening, said means including a longitudinally movable spring-pressed trigger.

In testimony whereof I affix my signature.
JOHN J. McNEELY.
